CLAIM

The ornamental design for a display screen with icon, as shown and described.

DESCRIPTION

FIG. 1 is a front view of a display screen with icon showing my new design;

FIG. 2 is a second embodiment thereof;

FIG. 3 is a third embodiment thereof; and,

FIG. 4 is a fourth embodiment thereof.

The broken lines showing an electronic device illustrate environmental subject matter, whereas the broken lines showing a display screen illustrate portions of the article and do not form part of the claimed design.
